UNITED STATES PATENT OFFICE.

CARL F. DIECKMANN, OF BUFFALO, NEW YORK.

TELESCOPE.

SPECIFICATION forming part of Letters Patent No. 788,823, dated May 2, 1905.

Application filed April 2, 1904. Serial No. 201,245.

To all whom it may concern:

Be it known that I, CARL F. DIECKMANN, a citizen of the United States, residing at Buffalo, in the county of Erie and State of New York, have invented new and useful Improvements in Telescopes, of which the following is a specification.

This invention relates more particularly to that class of telescopes in which prisms are employed for erecting the image and in which one of the prisms is adjustable relatively to the other, so that the instrument can be focused without changing the relation between the objective and the eyepiece. The improvements are especially desirable for opera-glasses, but are generally applicable to optical instruments employing a telescope.

One object of my invention is to improve the adjusting device of the movable prism, with a view of rendering it simple in construction and convenient of operation.

Another object is to provide an improved arrangement of the prisms which when employed in an opera-glass or similar binocular instrument permits the instrument to be made comparatively short, light, and compact.

The invention has the further objects to improve the construction of the eyepiece-tubes, so that they can be shortened when the instrument is not in use, and to improve the construction of the instrument in other respects.

In the accompanying drawings, consisting of two sheets, Figure 1 is a side elevation of an opera-glass embodying my invention. Fig. 2 is a front view thereof. Fig. 3 is an end view of the instrument. Fig. 4 is a longitudinal section of one of the main members of the instrument, the plane of the section being in line 4 4, Fig. 2. Fig. 5 is an enlarged interior view of the rear plate of one of the telescope-casings and the prisms mounted thereon. Fig. 6 is an external view of said plate. Fig. 7 is a cross-section, on a reduced scale, in line 7 7, Fig. 5. Fig. 8 is an enlarged longitudinal section of the front portion of the hinge which connects the two main parts of the instrument. Fig. 9 is a diagrammatic perspective view of the objective, prisms, and eyepiece of one of the telescopes. Fig. 10 is an enlarged longitudinal section of one of the

eyepieces. Fig. 11 is a sectional elevation of a field-glass containing a modified form of the invention. Fig. 12 is a longitudinal section of the telescope of a transit or other surveying instrument embodying the invention. Fig. 13 is a fragmentary longitudinal section showing another modification of the adjusting means of the movable prism.

Similar letters of reference indicate corresponding parts throughout the several views.

The opera-glass illustrated in Figs. 1 to 10 is of the type in which the two main members of the instrument are hinged together, so as to allow adjustment between the eyepieces to suit the pupillary distance of the observer's eyes. In the present instrument each of these main members comprises an oblong casing A, closed on all sides and containing the prisms, an eyepiece B, having the usual eye-lens B', and an objective-tube C, containing the usual objective-lens c.

The hinge between the main members may be of any suitable construction, but is preferably constructed as follows: The front and rear plates A' A² of each casing A are provided at their inner ends with eyes or perforated lugs d, which overlap those of the other casing, and these eyes are pivotally connected by a pintle or screw E, having a milled head e, for the purpose hereinafter described. This screw passes through the rear eyes of the hinge and is held against endwise movement by a nut e'. The opposite end of the screw is reduced and unthreaded and turns in a bearing-sleeve e², seated in the front hinge-eyes and having at its inner end a flange e⁴, which bears against the inner one of said eyes. The projecting front end of this sleeve is reduced and screw-threaded to receive a clamping-nut e⁵. Spring-washers e⁶ are preferably interposed between the nuts e' e⁵ and the hinge-eyes.

The objective-tubes C may be screwed or otherwise rigidly secured in openings in the rear plates of the casings A. Each of the eyepiece-tubes B is preferably composed of telescopic sections b b', so that the same may be shortened when not in use for reducing the size of the instrument. The inner section b of each tube, which forms an adapter, is

screwed or otherwise secured in an opening in the front plate A', while its outer section b', which forms the shell of the eyepiece, slides upon the inner section and carries a lens-tube 5 b². The latter fits into the fixed section of the tube B and is compelled to move with the outer section b' by a connecting-pin f, secured to the lens-tube b² and extending outwardly through a longitudinal slot f', formed in the 10 fixed tube-section b and into an opening in the sliding section b', as best shown in Fig. 10. By this construction the pin f also serves as a stop for limiting the outward movement 15 of the sliding tube-section on the fixed section. g is a spring arranged in said fixed tube-section between its head b³ and the opposing end of the lens-tube b² and tending to extend the sliding section b' to its outer normal position, as shown in the drawings. The 20 springs g allow the outer sliding tube-sections to be pushed inward on the fixed sections for shortening the eyepieces when the instrument is not in use, permitting the usual receiving-case of the instrument to be made correspond- 25 ingly shorter or shallower.

As shown in Figs. 3 and 4, the objectives are out of line with or above the plane of the eyepieces. Between the objective and the eyepiece of each half of the instrument are 30 located image-erecting prisms H H' of any suitable or well-known construction, the faces of which are in the proper relation to obtain the desired reflections. The two sets of prisms are alike, and a description of one set 35 will apply to both. They are arranged in the casing A, and the prism H is located in the optical axis, with its upper reflecting-surface h in opposing relation to the objective C and its lower reflecting-surface h' in similar relation to the eye-lens B', as shown in Fig. 9. The other prism, H', is arranged on the inner side of the prism H, with its reflecting-surfaces h² h³ opposite the respective surfaces h h' of the latter prism. The offset prism 40 H' is movable toward and from the prism H, or, in other words, in a plane at right angles to the optical axis, for the purpose of focusing the instrument, thus effecting the focal adjustment without changing the relation be- 45 tween the objective and the eyepiece. This adjustment of the movable prism of each set may be effected by any suitable means. In the preferred construction shown in the drawings the movable prisms H' of the two parts 50 of the instrument are moved away from the opposing prisms by springs i, suitably secured to the rear plates of the casings A and bearing against the inner sides of the movable prisms, and the latter are shifted toward the 55 fixed prisms by a wedge or conical nut J, engag- 60 ing the screw E and bearing at opposite sides against transverse shifting pins k, projecting from the backs of the adjustable prisms and passing through the inner ends of the cas- 65 ings, as shown in Figs. 1 and 5. The nut J

is provided in its periphery with a longitudinal groove j, which receives the outer end of one of the shifting pins k, so as to hold the nut from turning on the screw. By this construction upon turning the adjusting-screw forwardly the conical nut is caused to advance on the screw and shift the movable prisms H' toward the fixed ones, while upon turning the screw in the opposite direction said nut re- 70 cedes and allows the adjustable prisms to move away from the fixed prisms under the action of their return-springs i. Each movable prism is guided by a rib l, arranged on the inner side of the rear plate A² of the casing and fitting into a longitudinal groove l' in the oppos- 75 80 85 90 95 95 98 99 100 105 110 115 120 125 130 135 140 145 150 155 160 165 170 175 180 185 190 195 198 200 205 210 215 220 225 230 235 240 245 250 255 260 265 270 275 280 285 290 295 300 305 310 315 320 325 330 335 340 345 350 355 360 365 370 375 380 385 390 395 398 400 402 404 406 408 410 412 414 416 418 420 422 424 426 428 430 432 434 436 438 440 442 444 446 448 450 452 454 456 458 460 462 464 466 468 470 472 474 476 478 480 482 484 486 488 490 492 494 496 498 500 502 504 506 508 510 512 514 516 518 520 522 524 526 528 530 532 534 536 538 540 542 544 546 548 550 552 554 556 558 560 562 564 566 568 570 572 574 576 578 580 582 584 586 588 590 592 594 596 598 600 602 604 606 608 610 612 614 616 618 620 622 624 626 628 630 632 634 636 638 640 642 644 646 648 650 652 654 656 658 660 662 664 666 668 670 672 674 676 678 680 682 684 686 688 690 692 694 696 698 700 702 704 706 708 710 712 714 716 718 720 722 724 726 728 730 732 734 736 738 740 742 744 746 748 750 752 754 756 758 760 762 764 766 768 770 772 774 776 778 780 782 784 786 788 790 792 794 796 798 800 802 804 806 808 810 812 814 816 818 820 822 824 826 828 830 832 834 836 838 840 842 844 846 848 850 852 854 856 858 860 862 864 866 868 870 872 874 876 878 880 882 884 886 888 890 892 894 896 898 900 902 904 906 908 910 912 914 916 918 920 922 924 926 928 930 932 934 936 938 940 942 944 946 948 950 952 954 956 958 960 962 964 966 968 970 972 974 976 978 980 982 984 986 988 990 992 994 996 998 1000

The fixed prisms may be secured in place by any suitable means; but each of the same is preferably attached to a plate or mount m, 85 having a collar m', which is snugly fitted in the objective-tube C. This collar is of the proper length to bear against the inner side of the objective-lens, whereby the collar performs the additional function of retaining said lens 90 against the usual internal shoulder of the tube, as shown in Fig. 4.

According to the preferred construction of the casings A their front plates A' are cast integral with their sides, while their rear plates A² are separate and secured to the sides by screws n. (Shown in Figs. 5, 6, and 7.) In order to give the instrument a finished appearance, it is desirable to conceal the heads of these screws, and for this purpose the entire 100 outer surface of each rear plate except its marginal portion is provided with a covering n', of leather or other suitable material, which is cemented to the plate. For the purpose of finishing the front plates of the casings to correspond with the rear plates a leather covering n² is also applied to the front plates, as shown in Fig. 4. Around its edge each plate is provided with a bead or raised rib n³, which is flush with or slightly raised above the 110 leather covering and which may be electroplated to produce a neat finish. The screw-heads of the rear plate being inside of its bead and flush with the countersunk or depressed portions of the plate are hidden by the cov- 115 120 125 130 135 140 145 150 155 160 165 170 175 180 185 190 195 198 200 202 204 206 208 210 212 214 216 218 220 222 224 226 228 230 232 234 236 238 240 242 244 246 248 250 252 254 256 258 260 262 264 266 268 270 272 274 276 278 280 282 284 286 288 290 292 294 296 298 300 302 304 306 308 310 312 314 316 318 320 322 324 326 328 330 332 334 336 338 340 342 344 346 348 350 352 354 356 358 360 362 364 366 368 370 372 374 376 378 380 382 384 386 388 390 392 394 396 398 400 402 404 406 408 410 412 414 416 418 420 422 424 426 428 430 432 434 436 438 440 442 444 446 448 450 452 454 456 458 460 462 464 466 468 470 472 474 476 478 480 482 484 486 488 490 492 494 496 498 500 502 504 506 508 510 512 514 516 518 520 522 524 526 528 530 532 534 536 538 540 542 544 546 548 550 552 554 556 558 560 562 564 566 568 570 572 574 576 578 580 582 584 586 588 590 592 594 596 598 600 602 604 606 608 610 612 614 616 618 620 622 624 626 628 630 632 634 636 638 640 642 644 646 648 650 652 654 656 658 660 662 664 666 668 670 672 674 676 678 680 682 684 686 688 690 692 694 696 698 700 702 704 706 708 710 712 714 716 718 720 722 724 726 728 730 732 734 736 738 740 742 744 746 748 750 752 754 756 758 760 762 764 766 768 770 772 774 776 778 780 782 784 786 788 790 792 794 796 798 800 802 804 806 808 810 812 814 816 818 820 822 824 826 828 830 832 834 836 838 840 842 844 846 848 850 852 854 856 858 860 862 864 866 868 870 872 874 876 878 880 882 884 886 888 890 892 894 896 898 900 902 904 906 908 910 912 914 916 918 920 922 924 926 928 930 932 934 936 938 940 942 944 946 948 950 952 954 956 958 960 962 964 966 968 970 972 974 976 978 980 982 984 986 988 990 992 994 996 998 1000

By adjusting the prisms instead of the eyepieces or the objective for focusing the instrument the construction of the instrument is materially simplified and its cost of manufacture reduced accordingly. The improvement also permits a shorter and more compact construction of the instrument, enabling it to be held more steadily, while the arrangement of the movable prisms on the inner sides of the optical axes also contributes to the advantage of greater compactness by utilizing the central space between the eyepieces or tubes, while at the same time avoiding unsightly bulges at the outer sides of the tubes. 105 110 115 120 125 130 135 140 145 150 155 160 165 170 175 180 185 190 195 198 200 202 204 206 208 210 212 214 216 218 220 222 224 226 228 230 232 234 236 238 240 242 244 246 248 250 252 254 256 258 260 262 264 266 268 270 272 274 276 278 280 282 284 286 288 290 292 294 296 298 300 302 304 306 308 310 312 314 316 318 320 322 324 326 328 330 332 334 336 338 340 342 344 346 348 350 352 354 356 358 360 362 364 366 368 370 372 374 376 378 380 382 384 386 388 390 392 394 396 398 400 402 404 406 408 410 412 414 416 418 420 422 424 426 428 430 432 434 436 438 440 442 444 446 448 450 452 454 456 458 460 462 464 466 468 470 472 474 476 478 480 482 484 486 488 490 492 494 496 498 500 502 504 506 508 510 512 514 516 518 520 522 524 526 528 530 532 534 536 538 540 542 544 546 548 550 552 554 556 558 560 562 564 566 568 570 572 574 576 578 580 582 584 586 588 590 592 594 596 598 600 602 604 606 608 610 612 614 616 618 620 622 624 626 628 630 632 634 636 638 640 642 644 646 648 650 652 654 656 658 660 662 664 666 668 670 672 674 676 678 680 682 684 686 688 690 692 694 696 698 700 702 704 706 708 710 712 714 716 718 720 722 724 726 728 730 732 734 736 738 740 742 744 746 748 750 752 754 756 758 760 762 764 766 768 770 772 774 776 778 780 782 784 786 788 790 792 794 796 798 800 802 804 806 808 810 812 814 816 818 820 822 824 826 828 830 832 834 836 838 840 842 844 846 848 850 852 854 856 858 860 862 864 866 868 870 872 874 876 878 880 882 884 886 888 890 892 894 896 898 900 902 904 906 908 910 912 914 916 918 920 922 924 926 928 930 932 934 936 938 940 942 944 946 948 950 952 954 956 958 960 962 964 966 968 970 972 974 976 978 980 982 984 986 988 990 992 994 996 998 1000

My improved construction has the further advantage that the adjusting devices of the prisms do not extend beyond the sides of the casings and are fully protected from injury in case the opera-glass should be dropped. These adjusting devices, while permitting the instrument to be conveniently focused, do not interfere with the hinging action of the two parts of the glass.

10 The elevation of the objectives above the plane of the eyepieces is also a desirable feature in that the observer when using the opera-glass in a theater can better look over the heads of persons sitting in front of him.

15 As before stated, my improvements are also applicable to other instruments employing telescopes, such as field-glasses, astronomical instruments, and transits and other surveying instruments.

20 Fig. 11 shows a modified construction of the invention as applied to a field-glass. In this case the objectives are mounted in draw-tubes C' in a well-known manner. The casings A^3 are pivoted together to permit adjustment between eyepieces; but the hinge and the prism-adjusting devices are in this modification located on the rear side of the casings between the objective-tubes. Pintle-eyes d' are formed on parallel arms or brackets o , carried by the rear plates of the casings, and the head of the adjusting-screw E' is arranged at the rear end of the latter. The conical nut J' traverses this screw, as in the construction first described; but the pins k^2 ,

35 upon which the nut acts, instead of being attached to the movable prisms H^2 are carried by shifting-levers p . These levers are pivoted at their rear ends to the brackets o , while their free ends pass through longitudinal slots

40 p' in the rear plates of the casings and engage with the mounts m^2 of the movable prisms in such a manner that when the nut J' advances on the adjusting-screw the levers p shift the movable prisms H^2 toward the fixed prisms

45 H^3 . The movable prisms are shifted in the opposite direction by springs, as in the first-described construction. In order to permit the optical axis of one tube of the instrument to be shortened or lengthened with relation

50 to that of the other, if desired, one of the shifting pins—say the pin k^2 —preferably consists of an adjusting-screw, which engages a threaded opening in the corresponding lever, as shown. As the optical axis of the field-glass is longer than that of the opera-glass, a correspondingly greater movement of the movable prisms is required for the focal adjustment. This increased movement is obtained by employing the levers p , which multiply the throw or stroke of the conical nut J' .

An example of the invention in connection with the telescope of a surveying instrument is shown in Fig. 12. In this view q is the pivot upon which the telescope swings. The

65 objective and the eyepiece are of ordinary

construction. H^4 is the fixed prism, supported in a transverse casing A^4 , arranged partly inside and partly outside of the main telescope-tube, and H^5 is the adjustable prism, arranged in the projecting portion of the casing. The last-named prism is moved away from the fixed prism by a spring, as in the previous construction, and shifted toward the same by an adjusting-screw E^2 , passing through the closed outer end of the casing.

75 The invention is especially advantageous in such pivoted telescopes. As the focal adjustment is effected solely by moving one of the prisms, the telescope is not required to be lengthened or shortened, but always remains balanced in its bearings, thus obtaining close measurements and also preventing the ends of the telescope from striking the glass cover of the compass and causing injury or breakage of the parts, which is liable to occur in surveying instruments of ordinary construction when the telescope is lengthened. Moreover, as the relation between the eyepiece and the objective remains unchanged the line of culmination is not disturbed.

80 It is well known in the art that the greater the distance between the objective and the eyepiece the greater is the power of the instrument. As applied to surveying instruments my invention affords increased power 85 within a given space or distance, because the telescope requires no terrestrial eyepiece, no draw-tube for the objective, and hence no rack and pinion for operating such a tube.

90 In the modification of the invention shown in Fig. 13 a push-button E^4 is substituted for the adjusting-screw E^3 shown in Fig. 12. This construction permits the telescope to be focused with one hand and is therefore desirable for gun-telescopes and those used by 95 sportsmen.

100 From the foregoing description it is apparent that the invention is susceptible of various modifications without departing from its scope or spirit, and I do not, therefore, wish 110 to be limited to the particular embodiments of the same herein shown and described.

I claim as my invention—

1. In a telescope, the combination of an objective, an eyepiece, and opposing prisms interposed between the objective and the eyepiece, one of the prisms being located in the optical axis of the telescope and the other being movable at an angle to said axis, a spring for shifting the movable prism in one direction, and means for shifting the same in the opposite direction, substantially as set forth.

115 2. In an instrument of the character described, the combination of a pair of connected casings, an objective and a corresponding eyepiece applied to the front and rear sides of each casing, and a set of prisms arranged in each casing, one prism of each set being located in the optical axis of the corresponding objective and eyepiece and the other prisms 125

130

being located on the inner sides of the first-named prisms, whereby said inner prisms are arranged in the portions of the casings between the two telescope-tubes of the instrument, substantially as set forth.

3. In an instrument of the character described, the combination of a pair of connected casings each having an objective and an eyepiece which are fixed relatively to each other, 10 a set of prisms arranged in each casing, one prism of each set being fixed and located in the optical axis of the corresponding objective and eyepiece and the other prisms being independent of the eyepieces and objectives 15 and located on the inner sides of the first-named prisms and movable toward and from the same, and means for simultaneously adjusting said movable prisms, substantially as set forth.
- 20 4. In an instrument of the character described, the combination of a pair of connected casings each having an objective and an eyepiece, a set of prisms arranged in each casing, one prism of each set being located in the optical axis of the corresponding objective and eyepiece and the other prisms being movable toward and from the first-named prisms respectively and arranged on the inner sides 25 thereof, said movable prisms being provided 30 with shifting devices which extend through the walls of the casings, an adjusting-screw arranged between the two telescope-tubes of the instrument, and a wedge mounted on said screw and engaging said shifting devices, substantially as set forth.
5. In an instrument of the character described, the combination of a pair of connected casings each having an objective and an eyepiece, a set of prisms arranged in each casing, 40 one prism of each set being located in the optical axis of the corresponding objective and eyepiece and the other prisms being movable toward and from the first-named prisms respectively and arranged on the inner sides 45 thereof, shifting-levers for the movable prisms, and an adjusting-screw arranged between the two telescope-tubes of the instrument and having a wedge which engages said levers, substantially as set forth.
- 50 6. In an instrument of the character described, the combination of a pair of connected casings each having an objective and an eyepiece, a set of prisms arranged in each casing, one prism of each set being located in the optical axis of the corresponding objective and eyepiece and the other prisms being movable toward and from the first-named prisms respectively, shifting-levers for the movable 55 prisms, an adjusting-screw having a wedge 60 which engages said levers, and springs arranged to shift the movable prisms away from the opposing prisms, substantially as set forth.
7. In an instrument of the character de-

scribed, the combination of a pair of connected casings each having an objective and an eyepiece, a set of prisms arranged in each casing, one prism of each set being located in the optical axis of the corresponding objective and eyepiece and the other prisms being movable toward and from the first-named prisms respectively, shifting-levers for the movable prisms, one of said levers being provided with an adjustable pin or projection, an adjusting-screw arranged between said levers, and a wedge mounted on said screw and engaging said adjustable pin and the opposing lever, substantially as set forth.

8. In an instrument of the character described, the combination of a pair of connected casings each having an objective and an eyepiece, a set of prisms arranged in each casing, one prism of each set being located in the optical axis of the corresponding objective and eyepiece and the other prisms being movable toward and from the first-named prisms respectively, shifting-levers for the movable prisms, one of said levers being provided with an adjustable pin or projection, an adjusting-screw arranged between said levers and held 90 against endwise movement, and a conical nut traversing said screw and engaging said adjustable pin and the opposing lever, substantially as set forth.

9. In a telescope, the combination of an eyepiece, an objective-tube having an internal shoulder and an objective-lens seated against said shoulder, prisms interposed between the eyepiece and the objective, and a mount or support carrying one of said prisms and provided with a collar which fits into the objective-tube and holds the objective-lens against said shoulder, substantially as set forth.

10. In a telescope, the combination of a casing, an eyepiece comprising a stationary tube or adapter secured to the casing, a shell sliding upon said adapter, a lens-tube fitting in the adapter and connected with said shell, a spring arranged within the adapter and bearing at one end against an abutment and at its opposite end against the inner end of said lens-tube, whereby the spring tends to slide the lens-tube and the shell outwardly on the adapter, and means for limiting the outward movement of the lens-tube and shell on the adapter, substantially as set forth.

11. In an instrument of the character described, the combination of a casing having a plate provided around its edge with a raised bead, and a covering applied to the depressed portion of said plate bounded by said bead, substantially as set forth.

12. In an instrument of the character described, the combination of a casing having front and rear plates, one of which is removably secured thereto by suitable fastenings and provided around its edge with a raised bead, and a covering applied to the depressed

portion of said plate and concealing said fastenings, substantially as set forth.

13. In an instrument of the character described, the combination of a casing having front and rear plates, one of which is removably secured thereto by suitable fastenings, each of said plates being provided around its edge with a raised bead, and coverings applied to the depressed portion of said plates

and concealing said fastenings, substantially as set forth.

Witness my hand this 30th day of March, 1904.
